WOOD BLOCK

Continuation of application Serial No. 198,085, filed June 11, 1927. This application filed March 30, 1929.
Serial No. 351,435.

My invention relates to wood block flooring and one of the objects is to fabricate a wood block, from a plurality of strips, that will retain its shape and that can be manufactured cheaply.

Another object is to provide a use for short pieces of flooring. In the manufacture of flooring, many short lengths are produced which can not well be used by builders, because of the labor costs involved. In order to utilize these short pieces, any scheme contemplated must have so little manufacturing cost attached to it as that these short pieces can be made saleable at a profit. I fabricate these short pieces into structural units that are preferably square and securely bound together by metal ties fitting in registering grooves in the strips.

Such structural units may be laid directly on a wood or concrete subfloor with an interposed cement, and according to my invention, they lie perfectly flat and fit closely together so that they can be laid very rapidly.

The strips constituting the units are fastened together by metal ties engaging transverse grooves, preferably but not necessarily on the underside of the unit. When applied on the underside of the unit, the fastening means is so constituted that it will not project below the under surface and the unit will lie absolutely flat without rocking or tilting.

A further object of the invention is to provide a groove for the metal tie into which it can be dropped, as differentiated from such a device that is inserted endwise into the groove, which is often inconvenient if not sometimes impossible. In this way, it is possible to use a presser which flattens out the tie from above and forces its edges into tight contact with the wood.

With these and other objects in view, my invention consists of certain novel and peculiar features of construction and combination of parts, as will be hereinafter more fully described and particularly pointed out in the claims.

Referring to the drawings for a more complete disclosure of the invention:

Fig. 1 is a perspective of a block made up of flooring strips;

Fig. 2 is a bottom plan view;

Fig. 3 is an elevation illustrating one form of tie in initial position;

Fig. 4 is a similar view of such tie in final position;

Fig. 5 is an elevation of a modified form of tie in initial position;

Fig. 6 is a similar view of such tie in final position;

Fig. 7 is a detail view of the tie shown in Fig. 5; and

Fig. 8 is a detail view of a modified form of tie.

Flooring strips as customarily made have a groove 11 along one edge and a tongue 12 along the opposite edge. For making the block of my invention, the flooring strips 13, 14 and 15 are first cut to the same length. When making a block of the type that has three grooves and a single tongue, I take the individual strips so cut, and pass them through a machine that simultaneously cuts a groove 16 in each end and a groove 17 across the grain, in the back of the strip. These grooves may be cut by rotary cutter heads operating on each end and in the center of the strip simultaneously. Cutting all the grooves at the same time makes them more accurate. In making a block that has two tongues and two grooves, a tongue and a groove would be cut at opposite ends of each strip instead of a groove at each end as above explained. This only necessitates using a different type of cutter head for cutting a tongue instead of a groove.

In using a rotary cutter head, the sides of the groove 17 will necessarily be cut parallel and at right angles to the face of the strip. Such grooves are most readily and cheaply formed from a quantity production standpoint, but grooves of other shapes may be used if desired.

The several pieces of wood 13, 14 and 15 having been sawed to the desired length and grooved at the ends and on the underside, are laid flat with the underside up, on a table and brought together by having a press on each side of the block to force the tongues 12 and grooves 11 of the several strips together and then, while under pressure, the metal tie

18 is dropped into position in the groove 17, as shown in Figs. 3 and 5. Just sufficient pressure is put on the strips to cause the tongue and groove joints to fit tightly together, but without any substantial compression of the wood. If the wood in the strips is retained under too heavy compression in the finished block, any swelling of the strips due to moisture absorption will cause the block to buckle.

Pressure is applied to the entire outer surface of the tie to flatten it out and to bring its edges into sufficiently tight contact with the sides of the groove so as to hold the strips rigidly in assembled relationship. When using seasoned oak flooring strips, the wood is very hard and unless the metal tie is pressed at every point, it will buckle. With a metal tie of the shapes shown, the edges of the tie will fit in the angles of the groove 17 and when sufficient pressure is put on the tie, these edges will bite or sink into the wood, and hold the pieces securely together.

The tie is made preferably of malleable metal, such as cold rolled steel, and the metal should be of such gage as to provide a tie of sufficient stiffness so as to prevent warping or other displacement of the strips in handling the block. A tie of the shape shown in Figs. 3 and 4 will be stiffer than a tie that would be flat when in final position. When provided with a rib 19 as shown in Figs. 5, 6 and 7, additional stiffness will be given to the tie.

35 When the tie is in final position, no part of it should project beyond the plane of the back of the block; the reason for this being that the blocks are preferably laid directly on a level subfloor and in contact with it, which could not be done if there were any projections on the bottom of the block.

40 Teeth 20 may be provided along the edge of the tie to facilitate biting into the wood. Other forms of ties than those shown and 45 functioning in substantially the same manner will readily suggest themselves to those skilled in the art.

While the sides of the groove 17 are shown at right angles to the face of the block and 50 while this is the preferred form, it is clear that substantially the same results will be attained, if these sides should slope slightly towards or away from each other and the tie is dropped into position and then flattened out by pressing.

In the smaller sizes of blocks, a single tie and groove on the underside will be sufficient, but with the larger sizes more than one tie and groove may be used.

55 There is a decided advantage in dropping the ties into the grooves, rather than threading them in endwise, and also in having the edges of the groove bite into the wood. In view of the fact that the grooves 17 are cut in the individual strips before assembling,

it is difficult to secure exact alinement of the sides of the grooves 17. When the tie is dropped into position in the groove, this defect is immaterial, as well as when the edges of the tie bite into the wood.

70 The blocks may be held together by placing the ties in the end grooves 16. In such a case the tie should not be so deep as to contact with the tongue which enters that groove.

75 After the block has been assembled, it is then subjected to a waterproofing treatment, by impregnating with a suitable oleagenous composition, so as to prevent, or at least retard, moisture absorption. Unless subjected to such treatment, the block may warp and not remain perfectly flat; or the change of shape of the individual strips may throw the block out of square. The advantage of preventing these objectionable features are two-fold: (1) that the block will remain in shape 80 during transit and storage prior to use; (2) that it will remain in shape after being laid in the completed floor.

85 From the above description, it will be seen that I provide a fabricated block that can be manufactured cheaply from short strips of flooring that would otherwise be waste or of little value; that by using a stiff metal tie in combination with tongue and groove side 90 matching, the block has the desired rigidity; that by causing the stiff metal tie to bite into the wood, the strips are held together tightly; and that by waterproofing such block when 95 made, the same will keep its shape.

100 I am aware that my invention may be embodied in other specific forms without departing from the spirit or essential attributes thereof, and I therefore desire the present embodiment to be considered in all respects 105 as illustrative and not restrictive, reference being had to the appended claims rather than to the foregoing description to indicate the scope of the invention.

110 This application is a continuation of my application Serial No. 198,085, filed June 11, 1927.

I claim:

1. A structural unit comprising a plurality of strips of wood having in a surface thereof 115 a groove with parallel sides at right angles to the surface, and a metallic holder lying at the bottom of the groove with its edges sunk into the wood at the angles of the groove.

2. A structural unit comprising a plurality of strips of wood united along their longitudinal edges, by a tongue and groove joint, a groove cut transversely of the grain of the strips, a stiff metallic tie in the groove, the said tie having its edges forced into biting 120 contact with the wood, the tie being of sufficient stiffness to prevent warping or displacement of the strips relative to each other, the contact of the tie with the wood being sufficiently tight to hold the strips rigidly in as- 125 130

sembled relationship, the said tie being entirely within the outer surfaces of the unit.

3. A structural unit formed of assembled strips of wood free from warping comprising the combination to prevent warping of tightly-fitting tongue and groove joints between the adjacent strips, a groove crosswise of the strips, a stiff metallic tie in the groove embedded in the wood and in cooperation with the said tongues and grooves preventing movement of the strips in all directions relative to each other, the said wood being impregnated with a waterproofing composition.

4. A structural unit comprising a plurality of strips of wood united along their longitudinal edges by a tongue and groove joint, an open groove cut transversely of the grain of the strips, a stiff metallic tie in the said groove and embedded in the wood, and in cooperation with the said tongues and grooves, preventing movement of the strips in all directions relative to each other.

5. A structural unit comprising a plurality of strips of wood united along their edges by a tongue and groove joint, an open groove with parallel sides cut transversely of the grain of the strips, a stiff metallic tie in the said groove and in forced tight contact with the wood and in cooperation with the said tongues and grooves, preventing movement of the strips in all directions relative to each other.

In testimony whereof I affix my signature.
CHARLES W. ALLEN.
